UNITED STATES PATENT OFFICE.

JONATHAN P. B. FISKE, OF NEWTON, MASSACHUSETTS.

BURNING-KILN FOR BRICKS.

SPECIFICATION forming part of Letters Patent No. 683,643, dated October 1, 1901.

Application filed December 17, 1900. Serial No. 40,067. (No model.)

To all whom it may concern:

Be it known that I, JONATHAN P. B. FISKE, a citizen of the United States, residing at Newton, county of Middlesex, State of Massachusetts, have invented an Improvement in Burning-Kilns for Bricks, of which the following description, in connection with the accompanying drawings, is a specification, like characters on the drawings representing like parts.

10 My invention is an improvement in brick-kilns, and has for its primary object the provision of economical means for providing uniform burning of the bricks with a minimum cost of labor, fuel, and plant.

15 As at present usually constructed brick-kilns, especially of the continuous variety, are quite elaborate and expensive, inasmuch as they contain a more or less complex system of flues leading to a stationary and expensive

20 stack or chimney placed usually at a distance. These flues being contained in the walls of the kiln, or more often beneath the same, not only require large walls of superior construction to withstand the settling tendency due

25 to repeated heating and cooling, but give a very irregular draft, because of the changes in temperature of the atmosphere, which of course affects the drawing capacity of the stack and changes the temperature of the

30 earth and brickwork adjacent and constituting the flues. This irregularity and imperfection of draft and construction results also in irregular burning of the bricks, as the bricks in certain portions of the kiln-chambers are apt to be underburned or overburned, as the case may be. Accordingly I have pro-

35 vided the apparatus set forth in this specification, whereby the disadvantages above set forth are obviated and rapidity and uniformity of burning are secured at a minimum cost of plant, labor, and fuel.

I employ a forced draft and have herein shown a portable apparatus preferably arranged to travel over the top of the kiln and 45 provided with means for coöperating with the tops of the chambers or with the kiln-covers, as the case may be, at one point and another of the kiln as the burning therein progresses. When an ordinary draft is used, either that

50 provided by a stack in usual manner or in any other way, to produce a suction, the tendency is for cold air from the outside to

leak in through every crevice available, thereby producing a multitude of little streams of cold air impinging upon the adjacent bricks 55 and invariably injuring the latter, especially the color thereof, when the cold air strikes red-hot bricks. This is true to a very great extent around the doorways to the kiln-chambers, which are bricked up temporarily each 60 time the chamber is burned. This temporary brickwork is far from air-tight, the result being that a large number of "pale" or underburned bricks are produced around the doorways. I have discovered that this can all be 65 remedied simply by providing a forced draft instead of a suction-draft, the forced draft causing any leaks which may occur to take place outward, and therefore being incapable of injury to the bricks either in affecting their 70 color or uniformity of burning.

The structural details of my invention and various other matters thereof will be pointed out more fully in the following description, reference being had to the accompanying 75 drawings, in which I have shown a preferred embodiment of my invention, and the latter will be more particularly defined in the appended claims.

In the drawings, Figure 1 is a transverse 80 vertical section of a kiln constructed according to my invention and provided with my improved apparatus, parts being broken away for convenience of illustration. Fig. 2 is a vertical section taken on the line 22, Fig. 1. 85 Fig. 3 is a top plan view thereof.

Referring to the drawings, it will be seen that I have chosen to illustrate my invention in connection with a continuous kiln A, whose chambers *a* I have numbered for convenience 90 of reference; but it will be understood that my invention is not limited in its application to the kind of kiln shown, the word "chamber" including any division into which a kiln may be separated either permanently or otherwise. For the latter reason I have also omitted various details of construction of the kiln and have simply indicated a type of the kiln and have provided the same with openings *a'* through the roof and fire-holes *a²* through the 100 partition-walls *a³*, stacks of bricks being indicated in the chambers at *b*. Coöperating with the holes *a'* is a forced-draft apparatus C, herein shown as mounted on a truck *c*,

whose wheels c' travel on a track c^2 of any preferred construction. At one end the truck c is provided with a portable blower c^3 for producing a forced draft for driving the air 5 forcibly down into and through the bricks and successive chambers to such extent as may be required. This blower may be of any common construction, and therefore the details thereof will not be described. Connected

10 to the blower is a pipe c^4 , which is herein shown as provided with necks or branch pipes c^5 , projecting downwardly in alignment with the series of holes which the pipe c^4 is arranged to coöperate with, there being herein 15 shown merely for convenience of illustration six of these pipes coöperating with the six holes with which each kiln-chamber is shown as provided.

As a convenient means for quickly and accurately connecting and disconnecting the portable portion of the draft apparatus with the holes in the kiln-chambers I have connected the pipe c^4 and the blower c^3 by a flexible joint c^6 and have mounted the pipe c^4 on 20 friction-rolls c^7 , secured at opposite sides of the pipe to the truck, as clearly shown in Fig. 2. Each hole is provided with a sealing-cap a^4 . I do not claim the sealing-caps in themselves, as I avail myself of the kind already 25 used; but I use them with a different arrangement for producing certain new results, as will be pointed out more fully later on, and in this connection I regard them as forming an important feature of my invention.

30 35 The fire-holes are shown as provided with a projection or ledge a^5 for coöperating with a sealing damper or curtain a^6 . This curtain carries a weight or iron rod a^7 at its lower end and a plate a^8 and hooks a^9 at its upper end, so 40 that it may be lowered through the holes a' and dropped in position for sealing a fire-hole as may be required as the burning progresses.

Having thus described the leading details 45 of my apparatus, the operation is as follows: As shown in Fig. 2, chamber 1 is being emptied of burned bricks, and as the draft is a forced draft it follows that unless stopped it would flow backward as readily as it would 50 flow forward, and accordingly I apply the curtains or flue-stops a^6 to the fire-holes a^2 between the chambers 1 and 2, thereby preventing the air from the portable apparatus from flowing backward into chamber 2, and 55 thereby producing a "back draft" and obliging it to pass forward through the hot chamber 3 of burned bricks, the burning-chamber 4, and the hot chamber 5 of green bricks, and thence to the outer air. By forcing the air 60 under considerable pressure it is compelled to carry the heat into every part of the several chambers, and in this connection I desire to emphasize an extremely advantageous feature of my invention, this feature residing 65 in the extreme facility with which the draft may be equalized in the different portions of any chamber, as may be desired. If, for in-

stance, it be found that the bricks are not burning as rapidly in one forward corner of chamber 4 as they are in the rest of that chamber, I simply remove the sealing-caps a^4 from the holes a' in the adjacent corner of chamber 5, thereby producing a local draft and compelling the draft to quicken in the corner in question, or if it were the rear corner of the chamber that was being improperly burned the fault would readily be remedied by removing the caps at a' , as indicated in Fig. 3, which would direct a large portion of the draft to that part of chamber 4. By 80 having the forced draft, as explained, no cold jets of air can possibly strike against the hot bricks, because if there be any leakage it is necessarily all outward, and hence there is no possibility of deterioration from this 85 common cause. As the portable draft apparatus is all the time dealing with cold air and can therefore never become burned out, it is capable of very long life.

It will be understood that I do not claim the 90 provision, broadly, of a pipe and connections with openings in a kiln, nor do I claim the blower nor the truck, as each of these is old and used separately in other connections and for other purposes; but I do claim, broadly, 95 the forced draft, with portable means for applying it at various points about the kiln, and particularly the various elements of the apparatus when used together for accomplishing the results already set forth at length in 100 this description, and accordingly I do not intend to limit myself to the structural details, as many variations in arrangement and combination thereof may be resorted to without departing from the spirit and scope of my in- 105 vention.

In explaining the operation of the invention I have referred only to five chambers or sections, that being the portion of the kiln fully shown; but in practice the kiln will of 110 course contain any usual or preferred number of chambers and the circulation of the hot gases will take place through the usual number of said chambers, commencing at a chamber which is practically cold, passing 115 through a series of successively-hotter chambers to the burning-chamber, from which the waste gases are driven forward to heat the green bricks, until finally when cold said gases escape from the kiln.

Having described my invention, what I claim as new, and desire to secure by Letters Patent, is—

1. A kiln for bricks and the like, having a series of burning-chambers, draft-holes in 125 said chambers, and a portable forced-draft apparatus arranged to coöperate with said holes for forcing the draft into and through the chambers and contained stacks of bricks and means for preventing a back draft into 130 the chambers being emptied.

2. A kiln for burning bricks and the like, having a series of burning-chambers, a series of draft-holes in each chamber, a port-

able pipe with lateral branches arranged to coöperate with said draft-holes, and means for forcing air through said pipe into said chamber.

5 3. A kiln for bricks and the like, having a series of burning-chambers, draft-holes in said chambers, and a portable forced-draft apparatus arranged to coöperate with said holes for forcing the draft into and through the 10 chambers and contained stacks of bricks, combined with removable sealing-caps for closing said holes and permitting any of them, as may be desired, to be uncovered for creating local drafts in connection with said forced draft.

15 4. A kiln for bricks and the like, having a series of burning-chambers separated by walls provided with fire-holes, removable sealing dampers or curtains for said fire-holes, 20 and portable means for producing a forced draft in and blowing the air forcibly through said chambers.

25 5. A kiln provided with a series of burning-chambers, draft-holes through the roofs of said chambers, and a portable forced-draft apparatus for coöoperating with said draft-holes and forcing external air into and through said chambers, said portable apparatus including a blower for producing said 30 forced draft.

35 6. A kiln provided with a series of burning-chambers, draft-holes through the roofs of said chambers, and a portable forced-draft apparatus for coöoperating with said draft-holes and forcing external air into and through said chambers, said portable apparatus including a blower for producing said forced draft, and a pipe having branch connections adapted to coöperate simultaneously with a 40 series of said draft-holes.

45 7. A kiln for burning bricks and the like, having a plurality of chambers each provided with a series of draft-holes, combined with a portable forced-draft apparatus including a pipe and connections therefrom for coöoperating simultaneously with a series of draft-holes, means supporting said pipe and permitting the same to be rocked into and out of operative position.

50 8. A kiln for burning bricks and the like, having a plurality of chambers each provided

with a series of draft-holes, combined with a portable forced-draft apparatus including a pipe and connections therefrom for coöoperating simultaneously with said series of draft-holes, means supporting said pipe and permitting the same to be rocked into and out of operative position, a blower mounted on said supporting means, and a flexible-joint connection between said pipe and said blower for 60 permitting the pipe to be rocked relatively to the blower.

55 9. A brick-kiln having a plurality of chambers, draft-holes for said chambers, a track coöoperating with said series of chambers, a 65 truck movable on said track, a blower mounted on said truck, and a pipe also mounted on said truck and connected to said blower, said pipe having branch connections for coöperating with said draft-holes.

70 10. A kiln for burning bricks and the like, having a plurality of burning-chambers, each having draft-holes in the top, said chambers being separated by walls, fire-holes in said walls, and stopping devices capable of being 75 manipulated from the outside through said draft-holes for being placed in stopping position over said fire-holes, combined with a portable forced-draft apparatus for coöoperating with draft-holes of said kiln ahead of the 80 wall whose fire-holes have been closed by said stopping devices.

11. In a brick-kiln having a fire-hole provided with a ledge or projection at one side of the wall, and a stopping device therefor in 85 the form of a curtain provided with a plate and hooks in its upper end and weighted at its lower end.

12. A kiln for burning bricks and the like, having a series of connecting chambers or divisions, means for opening and closing communication between them, provision for a fire 90 for burning the bricks, and a forced-draft apparatus for blowing air to said fire and through a plurality of said chambers.

95 In testimony whereof I have signed my name to this specification in the presence of two subscribing witnesses.
